DESIGN FOR A CLOTHESPIN

John E. Most, Detroit, Mich.

Application May 15, 1944, Serial No. 113,590

Term of patent 14 years

(Cl. D17—6)

To all whom it may concern:

Be it known that I, John E. Most, a citizen of the United States, residing at Detroit, in the county of Wayne and State of Michigan, have invented a new, original, and ornamental Design for a Clothespin, of which the following is a specification, reference being had to the accompanying drawing, forming part thereof.

I claim:
The ornamental design for a clothespin, as shown.

JOHN E. MOST.
